HEEL-SEAT FITTING MACHINE

William S. Dallas, Beverly, Mass., assignor to
 United Shoe Machinery Corporation, Flemington, N. J., a corporation of New Jersey

Application July 25, 1940, Serial No. 347,450

4 Claims. (Cl. 12—31.5)

This invention relates to heel-seat fitting machines and is illustrated as embodied in improved mechanism for quickly and effectively positioning in said machines shoes to be fitted for heels of different sizes and styles.

Shoe manufacturers have recently been called upon to apply various new types of heels to shoes and, accordingly, it is desirable that commercial heel-seat fitting machines of the general type disclosed in United States Letters Patent No. 2,053,295, granted September 8, 1936, on an application filed in the name of Fred L. MacKenzie, shall be equipped to trim the heel-seat portions of the attached soles of said shoes for the reception of such heels. A spiral stop comprising part of the work positioning mechanism of the machine disclosed in said Letters Patent has a throw of only slightly more than an inch, and in order to provide heel seats varying in length from $\frac{3}{4}$ of an inch to 3 or more inches, it has been the practice to add extension blocks of different sizes to the back gage of the machine in order properly to position the various types of work, such, for example, as interlocking work, as disclosed in United States Letters Patent No. 2,170,842, granted August 29, 1939, on an application filed in the name of William D. Thomas. Because of various mechanical considerations, it is undesirable to increase the pitch or the size of the spiral stop of the machine with a view to avoiding the use of the above-mentioned extension blocks.

It is an object of the present invention to provide in a heel-seat fitting machine of the type above mentioned, heel gaging and shoe positioning mechanism which will accommodate all types of work without having to mount interchangeable extension blocks of various sizes and shapes upon the back gage of the machine as above described.

With the above object in view and in accordance with a feature of the present invention, there is provided a stop, a heel measuring gage comprising an abutment operatively connected to the stop, a movable member, a back gage which is adjustable with relation to said member and is constructed and arranged to be engaged by the rear end of a shoe to position said shoe lengthwise in the machine, markings for selectively locating the back gage in any one of several predetermined positions with relation to said member, and means comprising a pawl and recess arrangement for securing the positioned back gage to said member, the back gage and the member being movable by the shoe until said mem-

ber engages the stop, thereby positioning the shoe lengthwise in the machine in accordance with the length of the heel in the heel measuring gage.

- 5 In the illustrative machine said movable member has the form of a carrier slide to which a block constituting said abutment portion is pivoted. The back gage is mounted upon the forward end of a back gage slide which may be secured in different adjusted positions along a guideway of the carrier slide. Pivotedly mounted on the carrier slide are a pair of pawls one of which may be moved selectively into one of a plurality of recesses formed in the back gage slide when said back gage slide has been moved to a predetermined recognizable position along the guideway of the carrier slide. The proper setting of the back gage slide with reference to the carrier slide may be readily determined by 10 the operator through the provision of a line or marking which is formed at the upper surface of the back gage slide and may be moved into alignment with any one of a plurality of lines or markings on the carrier slide, the arrangement being 15 secured in different adjusted positions along a guideway of the carrier slide. Pivotedly mounted on the carrier slide are a pair of pawls one of which may be moved selectively into one of a plurality of recesses formed in the back gage slide when said back gage slide has been moved to a predetermined recognizable position along the guideway of the carrier slide. The proper setting of the back gage slide with reference to the carrier slide may be readily determined by 20 the operator through the provision of a line or marking which is formed at the upper surface of the back gage slide and may be moved into alignment with any one of a plurality of lines or markings on the carrier slide, the arrangement being 25 such that one of the pawls of the carrier slide falls into one of the recesses of the back gage slide when the line on the back gage slide is in alignment with one of the lines on the carrier slide.
- 20 With the above construction used in connection with interchangeable heel measuring and heel-seat fitting mechanism which will be described later, the above machine may be used to fit the heel seats of shoes for the reception of various 25 types of heels having attaching faces of the lengths of which differ considerably, without having to apply different extensions, such as above referred to, to the back gage.

The various features of the invention will be 30 understood and appreciated from the following detailed description read in connection with the accompanying drawings, in which—

Fig. 1 is a perspective view, partly in section and partly broken away, of heel measuring and 40 shoe positioning mechanism of an illustrative heel-seat fitting machine;

Figs. 2, 3 and 4 are detail views showing different portions of the shoe positioning mechanism;

Fig. 5 is a perspective view, partly broken away, 50 of a modified gage for measuring interlocking heels;

Figs. 6 and 7 are detail views of mechanism through which a heel-seat reducing knife of the 55 illustrative machine is operated; and

Fig. 8 is a perspective view of the heel end of

a shoe the heel-seat portion of the sole of which has been fitted for the reception of a Louis heel by the illustrative machine.

The illustrative machine is described with reference to fitting the heel-seat portion 20 (Fig. 1) of an attached sole 22 (Figs. 1 and 8) of a shoe 24 for the reception of a Louis heel 26, and comprises a heel gage 28 (Fig. 1) for measuring the heel lengthwise, a crease plate 30 for supporting the heel-seat portion 20 of the attached sole of the shoe, and means comprising a back gage 32 constructed and arranged to be engaged by the rear end of the shoe and movable rearwardly under pressure of the shoe until stopped by mechanism which will be described later, and which is set in accordance with the position of a movable abutment 34 of the heel gage.

The work supporting and trimming mechanism of the present machine, as well as the major portion of the illustrative heel measuring and shoe positioning mechanism of said machine, is disclosed in said Letters Patent No. 2,053,295, which may be referred to for a complete understanding of the machine and its operation.

Preparatory to presenting the shoe to the machine, the Louis heel 26, for example, which is to be attached to the shoe 24, is placed upon a table 36 of the heel gage 28 with its breast in engagement with a bar 38 which, as will appear later, when regular Cuban work is being operated upon, is swung into its dash line position shown in Fig. 1. In placing the Louis heel 26 upon the table 36, it is common practice first to force the rear end of the heel against the movable abutment 34 of the heel gage, causing said abutment to move rearwardly until the heel can be placed attaching face downward upon the table. The heel is then released, thereby enabling the movable abutment 34, operated through mechanism which will be described later and is similar to mechanism described in said Letters Patent No. 2,053,295, to force the breast of the heel with considerable pressure against the bar 38.

The abutment 34 is adjustably secured to a slide 42, movable in a guideway 44 of the table 36, by a clamp screw 40 which is threaded into the slide 42 and passes through a slot 41 in the abutment 34. In order to facilitate adjusting the abutment 34 upon the slide 42, there is provided a screw 43 which is threaded into the abutment and has a flange fitting in a slot 45 of the slide 42. Operatively connected through a slot-and-pin connection 46 to the slide 42 is a yoke 48 mounted upon a fulcrum pin 50 secured by a screw 52 to a bracket 54 of the machine frame. The yoke 48 is constantly urged in a clockwise direction, as viewed in Fig. 1, by a spring 56 one end of which embraces a stud 58 on the pin 50 and the other end of which embraces a stud 60 secured to the yoke, movement of the yoke in a clockwise direction when there is no heel in the heel gage being limited by a suitable stop.

The lower arm of the yoke has a geared segment 62 (Figs. 1 and 2) meshing with a pinion 64 (Fig. 2) which is mounted upon a fixed vertical fulcrum pin 66 and is secured to a spiral stop 68 which is mounted upon the fulcrum pin and which, through the above-described mechanism, may be set in different angularly adjusted positions in accordance with the position of the movable abutment 34 of the heel gage 28.

The back gage 32 has a pair of vertical channels 70 (Fig. 1) for receiving flanges 72 of a back gage slide 74. The back gage 32 is constantly urged to its raised position, shown in Fig. 1, upon

the back gage slide 74, by a spring 76 the lower end of which is connected through a plate 78 to a stud 80 secured to the back gage and the upper end of which embraces a stud 82 secured to the back gage slide.

The back gage slide 74, which is supported by the machine frame, fits in a guideway 84 (Figs. 1 and 4) of the carrier slide 86 and has an elongated slot 88 through which passes a block 90 which is pivoted upon a pin 92 secured to the carrier slide and may be referred to as the abutment portion of the carrier slide. Secured by a nut 94 to the carrier slide 86 and extending downwardly through an enlarged cylindrical recess 96 of the block 90 is a screw 98 a head 100 of which supports the block, the arrangement being such that the block may be swung about the axis of the pin 92 within limits determined by the screw 98. As will appear later, the block 90 is held in its idle position, shown in Figs. 1 and 2, by a spring 102 (Fig. 3) a coil portion of which embraces a pin 104 secured to the block, and end portions of which engage the screw 98 and a depending portion of the block 90, respectively. The rear face of the block 90 has an arcuate groove 106 which is of V-shaped cross section and has faces 108 shaped and arranged to engage opposed faces 110 of a tapered portion of the spiral stop 68 when, as will appear later, the block 90 is forced rearwardly against the spiral stop.

In order to vary the distance between the back gage 32 and the block 90, the back gage slide 74 may be secured in different adjusted positions to the carrier slide 86 through the provision of a pair of pawls 112 (Figs. 1 and 4) which are pivoted upon a pin 114 fixed to a bracket 116 secured by screws 118 (Fig. 1) to the carrier slide 86. The pawls 112 have heads 120 (Fig. 4), respectively, one of which may be inserted in one of a plurality of recesses 122 formed at the under side of the back gage slide 74. The heads 120 of the pawls 112 are constantly forced against the back gage slide 74 by spring-pressed plungers 124 housed in the bracket 116, the arrangement being such that the operator, after swinging the pawls against the action of the spring-pressed plungers 124, may selectively cause the head of one of the pawls 112 to register with one of the recesses 122 by moving the back gage slide 74 along the guideway 84 with relation to the carrier slide 86 to the proper position, the pawls then being released, thus causing the head of one of said pawls to register with the proper recess 122.

In order to enable the operator readily to adjust the back gage slide 74 in the carrier slide 86 in accordance with the particular type of work being operated upon in the machine, the back gage slide has a line 126 (Fig. 1) which may be moved into alignment with one of a plurality of lines 128 on the carrier slide, the arrangement being such that when the line 126 is in alignment with one of the lines 128, the operator releases the pawls 112, one of which is moved into an opposing recess 122.

In order to centralize the shoe in the machine, there is provided a bifurcated centralizing gage 130 which is slidably mounted in a guideway 132 of the machine frame. The centralizing gage 130 is constantly urged forwardly by springs 134 (only one of which is shown) which are located in cylindrical recesses of the centralizing gage 130 and are backed up by rods 136 the rear ends of which engage an arm 138 of the machine frame. Forward movement of the centralizing gage 130 under the action of the springs 134 is

limited by a stud 140 which is secured to the carrier slide 86 and has its upper end fitting in an elongated groove 142 of the centralizing gage 130, forward movement of the carrier slide being limited by the engagement of the bracket 116 with the arm 138 of the machine frame.

In positioning the shoe in the machine, the operator first forces the counterportion of the shoe against bifurcated portions 144 of the centralizing gage 130 which then moves rearwardly. The rear end of the shoe is then brought into engagement with the back gage 32 which, together with the centralizing gage 130, is moved rearwardly until the faces 108 of the groove 106 formed in the block 90 are forced against the faces 110 of the spiral stop 68, thereby preventing any further rearward movement of the shoe. As above described, the spiral stop 68 has already been swung to a predetermined position in accordance with the length of the heel 26 in the heel gage 28. It will be noted that due to the action of the spring 102 (Fig. 3), the left portion of the block (as viewed in Fig. 1) first engages the spiral stop, further rearward pressure exerted against the carrier slide 86 then causing the block to swing about the pin 92, with the result that the faces 108 of the block throughout their length are brought into registration with the opposed faces 110, respectively, of the spiral stop.

The spiral stop 68 has a low pitch, thus insuring that said stop shall not be rotated as the block 90 is forced rearwardly against it. Moreover, the spiral stop 68 is made small, as above stated, in order that it shall not interfere with the various operative parts of the machine, it being appreciated that the stop is made as light as practicable in order that it may be readily rotated in one direction when the movable abutment 34 is moved rearward by pressure of the heel against it, and may be moved to its gaging position by the spring 56 when the heel has been released in the heel gage 28.

As above stated, the fitted heel seats of shoes which are to receive the various types of heels above referred to, may vary from $\frac{3}{4}$ of an inch to 3 inches in length, and it has been found to be undesirable to provide the work positioning mechanism of the machine with a spiral stop having a throw of sufficient magnitude to accommodate such a wide range of sizes. By initially securing the back gage 74 in different adjusted positions to the carrier slide 86 and thereby varying the effective distances between the block 90 and the back gage 32, the small spiral stop 68 having a low pitch may be effectively used without having to secure to the forward end of the back gage extension blocks (not shown), such as described in said Letters Patent No. 2,170,842. It will be noted at this point that for a given type of work the initial setting of the heel gage 28 and the initial setting of the back gage slide 74 upon the carrier slide 86 shall be such that heel-breast receiving shoulders 146 formed upon the attached sole 22 of the shoe 24 are so located that they will be snugly engaged by the breast of the heel positioned upon the shoe.

In initially setting up the machine for Louis work, for example, the operator loosens the clamp screw 40 and after placing the Louis heel 26 upon the shoe 24 draws a heel breast line (not shown) across the sole of the shoe and then places the heel upon the table 36 of the heel gage 28 with the breast of the heel in engagement with

the bar 38. The back gage slide 74 is then locked to the carrier slide 86 with the line 126 of the back gage slide in alinement with line 128 arranged opposite the word "Regular" on the bracket 116 of the carrier slide. The shoe is next presented, heel end first, to the machine, the heel-seat portion 20 of the sole of the shoe overlying the crease plate 30 and the heel-breast line drawn across the sole being moved into alinement with front edges 148 of the crease plate, past which edges a cutting edge 150 of a shoulder forming knife 152 moves. The operator then, by the use of the yoke 48, swings the spiral stop 68 about the pin 66 until the faces 110 of the stop 10 are brought into contact with the faces 108, respectively, of the block 90, which has been forced rearwardly by the shoe. While holding the spiral stop in position the operator turns the adjusting screw 43 until the abutment 34 has been forced against the rear end of the heel and the breast of the heel has been forced against the bar 38. After the screw 43 has been turned to its final adjusted position, the clamp screw 40 is set, the arrangement then being such that the spiral stop 68 is so positioned by the heel that it will, by reason of its being engaged by the block, prevent rearward movement of the shoe in the machine when the heel-breast line of the sole 22 of the shoe 24 is in alinement with the front edges 148 20 of the crease plate 30. With the above arrangement, it will be clear that the length of the fitted heel seat of the shoe will be equal to the length of the attaching face of the measured heel to be attached to the shoe.

35 In order to set up the machine for operating upon Cuban work, a breast abutment 154 (Figs. 1 and 5), such as disclosed in said Letters Patent No. 2,170,842, is rotated 180° from its position shown in Fig. 5 in order that the breast of a 40 Cuban heel (not shown) to be attached to a shoe, the heel seat of which is to be fitted, may engage a curved face 156 of said abutment. As above stated, the bar 38 is swung to its dash line position shown in Fig. 1 before turning the breast 45 abutment 154 to an operative position. The Cuban heel is then placed, breast forward and attaching face down, upon the table 36 of the heel gage, and the shoe is moved rearwardly against the back gage 32 until a previously marked heel-breast line on the sole of the shoe is in alinement with the front edges of a crease plate which has previously been placed in the machine and is adapted for use in connection with Cuban work. After a few trial adjustments of a screw 50 55 158 through the provision of which the breast abutment 154 is moved lengthwise of the heel gage, the curved surface 156 of the abutment 154 is so adjusted that the spiral stop set by the heel in the heel gage will locate the shoe in the machine with its heel-breast line in alinement with the front edges of the crease plate. The throw of the stop 68 is sufficient to accommodate a full run of sizes of Louis and Cuban heels. Accordingly, in changing over from Louis to Cuban work, it is unnecessary to adjust the back gage slide 74 with relation to the carrier slide 86.

In initially adjusting the machine for the reception of interlocking work, the operator follows the same general procedure as above described in connection with Cuban work. It will be noted, however, that in operating upon interlocking work the line 126 of the back gage slide 74 is in alinement with line 128 on the carrier slide 86 opposite the word "Interlocking." As disclosed 75 in said Letters Patent No. 2,170,842, in order to

equip the machine for interlocking work, a platform 160 (Fig. 5) is placed upon the table 36 with its depending stud 162 fitting in a cylindrical recess 164 of the table, the bar 38 of the heel gage fitting in a groove 166 at the under side of the platform. After the shoe has been positioned in the machine, an interlocking heel 167 is placed upon the platform 160 with its breast in engagement with abutments 168, which are adjustably secured by screws 169 in grooves 171 formed in an upper portion 170 of the platform. The upper portion 170 of the platform 160 is normally secured to a base portion 172 of the platform by one or more screw-and-slot connections 174 but may be disconnected therefrom for purposes of adjustment, the arrangement being such that the upper portion 170 of the platform 160 is moved rearwardly with relation to said base portion 172 until the rear end of the heel, operating through the movable abutment 34 and the mechanism above described, causes the spiral stop to be forced against the block 90 which has been moved to its rearward operative position by the positioned shoe in the machine. The abutments 168 on the upper portion 170 of the platform 160 are then finally adjusted by trial and error with relation to the fixed lower portion 172 of the platform until the spiral stop accurately locates the shoe lengthwise in the machine. The screws 174 are finally tightened to secure the upper and lower portions 170, 172, respectively, of the platform 160 together.

Platforms which are similar to the platform 160 are provided for use in connection with short Cuban and long slipper heels, for example, the back gage slide 74 being previously adjusted with relation to the carrier slide 86, as above described, before effecting the setting up adjustment. It will be readily appreciated from the foregoing that the machine is readily adapted to accommodate the various types of work by replacing certain parts of the machine for others and without having initially to set up the machine each time that the type of work is changed.

When the machine is equipped for reducing the heel-seat portions of the attached soles of men's slippers, for example, for the reception of heels, the U-shaped opening of the crease plate used is extremely large and it has been found desirable to increase the extent of the backward movement of a heel-seat reducing knife 176 so that said knife shall start its cut well rearward of said opening. It will be appreciated that when operating upon the various types of work except interlocking work, in which case the heel-seat reducing knife is removed, the forward movement of the heel-seat reducing knife 176, which is movable along a flat bottom face of the crease plate, ceases when its cutting edge 178 reaches the heel-breast line of the sole of the shoe, which line, when the shoe is positioned in the machine, extends along the front edges 148 of the crease plate. In order to increase the rearward throw of the heel-seat reducing knife 176, a connecting lever 180, similar to a corresponding lever of the machine disclosed in United States Letters Patent No. 2,053,295, has secured to its upper end a housing 182 having a recess 184 for receiving a lug 186 of a bell-crank lever 188, similar to a corresponding bell-crank lever of the machine disclosed in said Letters Patent. The upper end of the bell-crank lever 188 is pivoted to a rod 190 pivoted to a carrier slide 192 which is mounted for forward and rearward sliding movement along a guideway 194 of the

machine frame and has secured to it the heel-seat reducing knife 176.

Threaded into an extension of the housing 182 is a screw 196 an end portion of which is constructed and arranged selectively to fit in one of two recesses 198, 200 of the lug 186. The recesses 198, 200 are so arranged that when the heel-seat reducing knife 176 is at the forward end of its stroke with its cutting edge 178 in alinement with the forward edges 148 of the crease plate, the recesses are centered about the axis of a pivot pin 202 to which the lower end of the connecting lever 180 is pivoted. When the machine is operating upon various types of work except men's slipper work, the screw 196 registers with the recess 198, but when the machine is operating upon men's slipper work, the screw registers with the recess 200, thereby causing the heel-seat reducing knife 176 to be retracted further than in other types of work. By causing the recesses 198, 200 to be centered about the axis of the pivot pin 202 when the cutting edge of the heel-seat reducing knife 176 is at the forward end of its cutting stroke, it will be appreciated that the forward movement of the knife will at all times cease when the cutting edge 178 of the knife 176 arrives at the forward edges 148 of the crease plate 30.

Having described my invention, what I claim as new and desire to secure by Letters Patent of the United States is:

1. A heel-seat fitting machine having, in combination, a stop, a measuring gage which comprises a movable abutment constructed and arranged to engage one end of a heel and which comprises a fixed but readily interchangeable abutment constructed and arranged to engage an opposite end of the heel, mechanism for connecting said movable abutment to the stop to move said stop into different operative positions in accordance with the position of said movable abutment, a member constructed and arranged to be moved into engagement with the stop, a back gage which is adjustable with relation to said member and is constructed and arranged to be engaged by the rear end of a shoe to position said shoe lengthwise in the machine, markings for selectively locating the back gage in any one of several predetermined positions in accordance with the particular fixed abutment used in the heel measuring gage, and means comprising a pawl and recess arrangement for securing the positioned back gage to said member, said back gage and said member being movable under pressure of the shoe until said member is moved against the stop thereby positioning the shoe lengthwise in the machine in accordance with the length of the heel in the heel measuring gage.

2. A heel-seat fitting machine having, in combination, a spiral stop, a measuring gage which comprises a movable abutment constructed and arranged to engage one end of a heel and which comprises a fixed but readily interchangeable abutment constructed and arranged to engage an opposite end of the heel, means for initially positioning said fixed but readily interchangeable abutment upon said measuring gage in accordance with the particular type of heel to be measured, a back gage constructed and arranged to be engaged by the rear end of a shoe to position said shoe lengthwise in the machine, a slide, a block pivoted to the slide, a spring for maintaining the block in a predetermined angular position with relation to the slide when the machine is idle, and means for securing the back

gage in different readily recognizable positions to the slide to vary the distance between the back gage and the block, said back gage being movable by pressure of the shoe against it, the block upon said movement of the back gage being moved into contact with surface portions of the stop and then being swung relatively to the stop against the action of the spring to engage additional surface portions of the stop thereby positioning the shoe lengthwise in accordance with the length of the heel in the heel measuring gage.

3. A heel-seat fitting machine having, in combination, a spiral stop, a heel measuring gage comprising a movable abutment operatively connected to said stop, a back gage constructed and arranged to be engaged by the rear end of a shoe, a slide, a block pivoted to the slide, means comprising markings for selectively locating the back gage in any one of several predetermined positions with relation to the slide, and means comprising a pawl and recess arrangement for securing the positioned back gage to the slide, said back gage being movable by pressure of the

shoe against it until said block engages the stop thereby positioning the shoe lengthwise in the machine in accordance with the position of the movable abutment of the heel measuring gage.

- 5 4. A heel-seat fitting machine having, in combination, a spiral stop, a heel measuring gage comprising a movable abutment operatively connected to the stop, a back gage constructed and arranged to be engaged by the rear end of a shoe, a slide, a block pivoted to the slide, a spring for maintaining the block in a predetermined angular position with relation to the slide when the machine is idle, and means for securing the back gage in different adjusted positions relative to 10 the slide to vary the distance between the block and the back gage, said back gage being movable by pressure of the shoe against it until said block engages the stop and swings in opposition to the action of the spring against the stop thereby 15 positioning the shoe lengthwise in accordance with the position of the movable abutment of the heel measuring gage.

WILLIAM S. DALLAS.
